UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL PRESS.

Application filed April 27, 1918. Serial No. 231,160.

To all whom it may concern:

Be it known that I, ERASTUS E. WINKLEY, a citizen of the United States, residing at Lynn, in the county of Essex and State of Massachusetts, have invented certain new and useful Improvements in Heel Presses; and I do hereby declare the following to be a full, clear, and exact description of the invention, such as will enable others skilled 10 in the art to which it appertains to make and use the same.

This invention relates to heel-presses for maintaining pressure upon newly built heel-piles, composed of superposed lifts that are 15 pasted together, during the setting or drying of the paste, and is designed primarily as an improvement of the heel-press disclosed in applicant's copending application, Serial No. 156,824, filed March 23, 1917, al- 20 though the several features of the invention are also applicable to other machines of this general class.

The machine set forth in the above-indicated application is a power operated ma- 25 chine and comprises a rotatable carrier which supports a plurality of heel-clamps to which heels are supplied by an auxiliary feeding device. The carrier and clamps are rotated step-by-step past the feeding station 30 by means of a power driving mechanism, which, under the control of the operator, is thrown into operation, and which, through the agency of a single revolution clutch, is automatically disconnected to permit the 35 carrier to come to rest. Power is also utilized to set and release the heel-clamps and to eject the heels therefrom after the paste has dried and the clamps are released.

One of the objects of the present inven- 40 tion is to so modify, simplify and improve the construction of the prior machine that it may be operated with a minimum expenditure of energy by the operator by means of a foot-treadle mechanism.

Another object is to provide an improved 45 ejecting mechanism which shall operate with reliability and effectiveness to discharge the heels from the heel-clamps.

In accordance with the present invention, 50 one of the features thereof resides in a treadle mechanism and a co-operating double-acting unidirectional ratchet device whereby the various instrumentalities of the

machine may be operated with facility by foot-power supplied by the operator. 55

Another feature of the invention com- 60 prises an ejector for discharging heels from the clamps after the paste has set, and this ejector is first slowly advanced to gradually release the heel from its clamp in the event that excess paste causes it to adhere thereto, after which the ejector is rapidly projected to kick the heel free from the clamp and discharge it into a suitable receptacle. 65

The two features of the machine just de- 70 scribed, namely the improved operating treadle and improved ejector mechanism, are the only features to be claimed in this application. Many other features of the machine to be described, including the press 75 actuating and heel ejecting devices in aspects and combinations other than as claimed herein, are novel and patentable, but claims to these features and combinations will be found in my earlier filed co-pending appli- 80 cations Ser. No. 156,824, filed March 23, 1917, hereinbefore named, Ser. No. 67,814, filed Dec. 20, 1915, and Ser. No. 137,837, filed October 19, 1916.

To the accomplishment of the objects 85 named the invention comprises the features and combinations of parts hereinafter de- 90 scribed and then particularly pointed out in the appended claims, reference being had to the accompanying drawings illustrating the 95 preferred embodiment of the invention.

In the accompanying drawings, Figure 1 100 is a view, partially in side elevation and partially in section, of a heel-press embodying the present invention, certain parts being broken away for the sake of clearness; Fig. 2 is a detail view showing part of the mechanism for opening the heel-clamps; Fig. 3 is a partial plan view of the machine, a portion of one member thereof being broken 105 away for clearness; Fig. 4 is a plan view in section on the line 4—4 of Fig. 1, showing the foot-power operating mechanism; Fig. 5 is a side elevation of a portion of the unidirectional ratchet device; Fig. 6 is a sectional view on the line 6—6 of Fig. 1, illustrating the ratchet device and cams operated thereby; and Fig. 7 is a plan view of a portion of the heel ejector, showing the parts in their outward projected position. 110

Referring to the drawings illustrating the

preferred embodiment of the invention, the machine is, in general, similar in construction and operation to the machine set forth in the aforesaid copending application, and 5 comprises a supporting frame 10 upon which the various parts of the machine are mounted; a carrier 12 rotatably mounted upon the supporting frame; a plurality of normally closed heel-clamps 14 disposed on the periphery of said carrier for severally holding freshly pasted heels under pressure until the paste has set; a retractor 16 and actuating mechanism therefor including a cam 18 for effecting the release of the successive heel-clamps at the ejecting and loading station; an operating mechanism including a cam 20 for advancing the carrier and associated heel-clamps in step-by-step movement past the ejecting and loading station; a yielding buffer 22 and means for effecting its actuation including an operating lever 24 for arresting the movement of the carrier as the several heel-clamps are brought into the ejecting and loading station; a combined gage and ejector 26 and operating mechanism therefor including a cam 28 for gaging the position of the heels as they are introduced into the clamps and for subsequently ejecting them; and a main power mechanism for intermittently turning the operating cams through a single revolution whereby the various parts of the machine are caused to function through a complete cycle of operation.

35 Except for the details of construction and operation of the ejecting mechanism and the main power mechanism, the machine is like that disclosed in the above mentioned copending application, and therefore only a 40 brief and general description of the common features of the machine will be given, reference being had to said application for a more detailed description, if desired.

45 The supporting frame 10 embodies a central pedestal 30 which supports an upwardly projecting stationary sleeve or tube 32. Rotatably mounted upon the tube 32 and resting upon the upper end of the pedestal 30 is a hub 34 which is provided with a rigid arm 36 that is periodically reciprocated by suitable mechanism that is actuated by the cam 20. The outer end of the arm 36 carries a pawl 37 which is adapted to engage a series of projections 38 upon the rotatable carrier 12 whereby the carrier is advanced step-by-step, as will be understood.

50 The carrier 12 comprises three annular members 40, 42 and 44, the intermediate member 40 being supported by radial ribs 46 from a hub that loosely surrounds the stationary tube 32 and rests upon the upper end of the intermediate hub 34. The carrier member 42 is disposed beneath the member 40 and is fixedly secured thereto by up-

rights 48, while the carrier member 44 is adjustably supported above said carrier member 40 by means of a series of threaded rods 50.

55 The respective heel-clamps 14 severally comprise an upper jaw 52 that is pivotally suspended from the upper carrier member 44, and a lower jaw 54 that is fixed at the upper end of a vertical rod 56 that is carried by and loosely mounted in the carrier members 40 and 42. The rod is surrounded by a spring 58 that normally serves to hold the lower clamp jaw in its raised or clamping position. The lower end of the rod 56 is provided with a laterally projecting member 60 (Fig. 2) that is adapted to be engaged by the upper hooked end 62 of the retractor 16 when the heel-clamp is brought to the ejecting and loading station.

60 In order to arrest the movement of the carrier 12 as it is advanced step-by-step to bring the heel-clamps 14 successively into position in which the clamps are released, the heels ejected, fresh heels loaded therein, and the clamps reset, the buffer 22 is periodically projected into the path of movement of projections 38 hereinbefore mentioned.

65 As the successive heel-clamps 14 occupy this position or station, the cam 18 functions through the mechanism associated therewith to cause the retractor 16 to hook over the laterally projecting members 60 of said clamps and to draw down the lower clamp jaws 54 to release the clamps.

70 Assuming one of the heel-clamps to be released in the general manner just indicated, the next operation is to release the heel, if it chance to be stuck to the heel-clamp, and to subsequently effect its ejection or discharge. As already stated, one of the 75 features of the present invention lies in the improved type of ejecting mechanism and, therefore, said mechanism will now be described in detail.

75 The ejector 26, which is adapted to perform the function of a gage for positioning a fresh heel as it is loaded into a clamp as well as to kick out and discharge a dried heel, is located at the ejecting and loading station and cooperates with the several heel-clamps 14 as they are successively brought to said station. The actuation of the combined gage and ejector is in a substantially radial outward direction, and it 80 has three salient positions, one in which it is fully retracted to permit the rods 50 of the carrier 12 to pass as the carrier is advanced, one in which it acts as a gage and which is illustrated in dotted lines in Fig. 8, and one in which it is fully projected after 85 having discharged a heel and in which it is shown in Fig. 7.

90 The ejector 26 is adjustably secured by means of a bolt-and-slot connection 66 to the outer end of a horizontally and radially dis-

posed bar 68 that is slidably positioned upon the upper surface of a slide 70 (Fig. 1), being guided by the lateral flanges of an inverted channel-shaped member 72 that is secured to said upper surface. The slide 70 is rigidly secured to a sleeve 76 that is integrally associated by means of a yoke 78 with another sleeve 80, said sleeves being slidably mounted upon a horizontal guide rod 82. This guide rod is mounted in stationary position in a block 84 which is fixed upon the upper end of the tube 32 and rotation of said sleeves upon said rod is prevented by an arm 86 that projects from the sleeve 80 and is provided with an opening to receive a second guide rod 88 that is also fixed to the block 84.

The inner end of the bar 68 is provided with a pin 90 that projects upwardly through a slot 92 in the channel shaped plate 72, and the ejector 26 is normally maintained in its extreme inner position with respect to the slide 70 by means of a latch 94 that is pivotally mounted upon the pin 90 and the end of which is adapted to engage an angular shoulder 96 on the inner side of a lug 98 that is provided upon the channel shaped member 72.

The latch 94 is biased or held in its engaging position by means of a spring 100 having one of its ends secured to a pin 102 that is carried by the latch 94 and its other end suitably fastened to the channel shaped member 72. The latch 94 is provided with a lug 106 that projects laterally beyond the side of the slide 70, by means of which the latch 94 is tripped in a manner to be set forth. The pin 90 is straddled by a bifurcated end 110 of a lever 112 that is pivoted upon a pin 114 that is carried by the sleeve 76. The other end of the lever 112 is connected to one end of a spring 116 having its opposite end fastened to a pin 118 that projects from the yoke member 78. The spring 116, therefore, tends to actuate the lever 112 in such a direction as to project the ejector 26 outwardly whenever the bar 68 is released by the tripping of the latch 94.

The slide 70 and the associated sleeves 76 and 80 are actuated by means of an L-shaped link 120, the angle of which is pivotally connected to the slide 70 by means of a pin 122. The L-shaped member 120 is provided with a short angularly disposed and rigid arm 124 that is adapted to cooperate with a cam surface 126 upon the lever 112 for the purpose of withdrawing the ejector 26 and setting the latch 94, as will be more fully set forth. The inner end of the L-shaped member 120 is pivotally connected to an arm 130 that is fixed on the upper end of a rock shaft 132 that loosely projects through the stationary tube 32. The lower end of the rock shaft 132 is provided with an arm 134 (Figs. 1 and 4) which is connect-

ed by a universal joint 136 to a rod 138 having a universal connection 140 to the lower end of an arm 142. This arm is integral with a hub 144 that turns on a shaft 146 that is suitably supported by the frame of the machine. The hub 144 is also provided with an arm 148 that carries a roller 150 which cooperatively engages a cam path in the cam 28, said cam being fixed to a cam sleeve or quill 152 that is rotatably mounted upon a shaft 154 that is supported by the machine frame.

At this point, it may be well to note that the retractor cam 18 and the carrier-advancing cam 20 are also fixed to the quill 152. For purposes of the present explanation, it will merely be assumed that suitable mechanism is provided for rotating the cam-quill and the cams attached thereto, whereby the ejector 26 and all of the other mechanisms of the machine hereinbefore described are actuated. The particular mechanism for rotating the quill and cams constitutes an important part of the present invention and will be hereinafter described in detail.

Returning to the description of the ejecting mechanism, the operation thereof will now be set forth.

As shown in Fig. 3, one of the heel-clamps 14 is at rest at the ejecting and loading station, said clamp having been released, the heel ejected and the ejector 26 retracted to its gaging position, in which it is adapted to position the breast surface of the fresh heel that is introduced into the clamp by the operator. After having loaded a heel into the clamp and in engagement with the gage, the quill 152 and associated cams 18, 20 and 28 are actuated through the agency of suitable mechanism to be later set forth.

As the cam 28 rotates, its associated mechanism causes the arm 130 at the upper end of the rock-shaft 132 to be actuated in a counter-clockwise direction to cause the L-shaped member 120 to pull in the slide 70 and associated sleeves 76 and 80. As the angularity between the arm 130 and the member 120 decreases, the short arm 124 of the L-shaped member 120 engages the cam 126 on the lever 112 and forces in said lever and associated ejector bar 66 and ejector 26 against the action of the spring 116 until the end of the latch 94 drops into the angular notch or shoulder 96 in the lug 98, whereby the ejector 26 is set and latched to the movable slide 70. The continuation of the counter-clockwise movement of the arm 130 effects a further retraction of the slide 70 and the ejector 26, that is latched thereto, until said ejector is withdrawn to its extreme inner position. After the ejector 26 has been withdrawn from the clamp, the cam 18 and its associated mechanism causes the retractor 16 to permit the clamp 130

to close upon the fresh heel and place it under pressure.

The carrier 12 is then advanced by means of the cam 20 and the carrier-operating mechanism that is actuated thereby to bring the next succeeding heel-clamp into the ejecting and loading station. Under these conditions, the cam 18 and the mechanism associated therewith causes the retractor 16 to release the heel-clamp that is then in position, after which the continued rotation of the cam 28 actuates the rock shaft 132 and upper arm 130 in a clockwise direction. In so doing, the slide 70 and the ejector 26, which is set and latched thereto, are moved outwardly, bringing the latter into engagement with the heel that is in position in the heel-clamp that has just been released. As the ejector is thus actuated, the heel, which may have adhered to the clamp by reason of the excess of paste employed, is released therefrom.

At this point in the operation, the toggle formed by the arm 130 and the member 120 has been straightened out to such an extent that the inner side of the member 120 is brought into engagement with the lug 106 on the latch 94. Thereupon, the latch is forced out of engagement with the angular shoulder 96 of the lug 98 on the channel member 72 and the spring 116 suddenly acts upon the lever 112 to cause the bar 68 and the ejector 26 to be rapidly projected in an outward direction to kick the heel out of the clamp and free from the machine. The positions of the parts of the ejecting mechanism under these conditions are shown in Fig. 7.

The partial retraction of the ejector 26 to its initial gaging position, as illustrated in Fig. 3, is then effected by the cam 28 through the mechanism hereinbefore described, it being understood that during this movement, the spring 116 is being placed under tension at the same time that the slide 70 and the ejector 26 are being withdrawn. The cycle of operation is then completed and the machine comes to rest.

From the foregoing description of the ejecting mechanism, it will be understood that any heels that have adhered to the heel-clamps are first loosened by the positive operation of the mechanism under the control of the cam 28, after which the ejector 26 is caused to suddenly impel the loosened heel from the clamps by means of the auxiliary spring actuated device above described.

Having set forth in detail the construction and operation of the improved ejecting mechanism, the other feature of the invention which pertains to the means for supplying power to the cam-quill and operating cams, and which constitutes a foot-power treadle mechanism operating in conjunction

with a double-acting unidirectional ratchet device, will be described.

In the foregoing description, it has been assumed that suitable means for rotating the cams 18, 20 and 28 upon the cam-quill 152 is provided. The particular means for effecting this operation, and which so modified the construction and operation of the heel-press of the prior copending application that it may be effectively operated by foot-power with a minimum expenditure of energy, comprises a gear wheel 160 that is integrally associated with the quill 152 and which cooperates with a gear wheel 162 of twice the diameter. This gear wheel 162 is provided with a hub 164 by means of which it is rotatably mounted upon the shaft 146. Fixed to the hub 164 of the gear wheel 162 is a disk or ratchet member 166 having a plurality of notches 168, 170, 172 and 174 provided in its periphery and disposed in pairs diametrically opposite one another. The notches 168 and 172 are located on one side of the disk and the other pair of notches 170 and 174 on the opposite side thereof.

In order to actuate the ratchet 166 and associated gear wheel 162 step-by-step in a single direction, a plurality of pawls 176 and 178 are provided, which are adapted respectively to cooperate with the notches 168 and 172 on one side of the disk, and with the notches 170 and 174 on the opposite side thereof. The pawl 176 is pivotally mounted upon a pin 180 that is carried by and projects between arms 184 and 186 that are respectively loosely mounted upon the shaft 146 and upon the hub 164 of the gear wheel 162, while the pawl 178 is similarly mounted upon a pin 188 that projects between arms 190 and 192 that are respectively loosely mounted upon the hub 164 and upon the shaft 146. A spring 194 is connected to the pawl 176 and the arm 184 and tends to maintain said pawl in engagement with the periphery of the ratchet or disk member 166, while the spring 196 performs a similar function in connection with the pawl 178.

Pivotally connected to the associated arms 184 and 186 that carry the pawl 176 is a link 198, the upper end of which is located between said arms and is pivotally mounted upon a pin 202 that is carried thereby. The upper end of a link 204 has a similar pivotal connection upon a pin 206 to the associated arms 190 and 192. The several links 198 and 204 are curved outwardly in opposite directions, and the lower ends thereof are respectively pivotally connected to a foot-treadle 208 by means of pins 210 and 212. The foot-treadle 208 is pivoted at one end to the machine frame 10 upon a stud 214, and the free end thereof constitutes a pedal 216 upon which the operator steps in operating the machine.

The treadle 208 is normally held in its

raised position by means of a heavy compression spring 218 which acts thereon through the medium of a chain 220. The spring 218 surrounds a cylindrical sleeve or pipe 222 that is conveniently screwed into a plate or bracket 224 which is mounted upon the machine frame, and disposed within said sleeve or pipe is a slidable rod 226, the outer end of which is provided with a washer 228 and an adjusting nut 230 against which the end of the spring 218 abuts. The inner end of the rod 226 is connected to the chain 220 which projects through an opening in the plate or bracket 224 and passes over a loose pulley 232 that is held on the shaft 154 by means of a collar 234. The other end of the chain is attached to the treadle 208 by means of a pin 236.

Assuming the treadle mechanism to occupy its raised normal position, the operation of the treadle mechanism, ratchet device and the several cams and their associated operating mechanisms is effected in the following manner:— When the operator has placed a fresh heel into an open clamp at the loading station, he steps upon the foot-pedal 216 of the treadle 208 and forces it into its depressed position. In so doing, the pawl 178 drops into one of the notches 170 or 174 on the remote side of the ratchet disk 166 and, as the curved link 204 is moved downwardly, said pawl 178 effects the clockwise rotation of the disk 166 and associated gear wheel 162. As the gear wheel 162 is actuated through substantially a quarter turn, the cooperating gear wheel 160, and therefore the quill 152 and associated cams 18, 20 and 28, are rotated through a half revolution, whereby the various actuating mechanisms of the machine are partially operated in the manner already described. The positions of the parts of the foot-power treadle mechanism and ratchet device, when the treadle 208 occupies its depressed position, are as shown in Fig. 1. During the depression of the treadle 208, the power spring 218 is compressed, whereby energy is stored therein which is utilized to return the treadle 208 and the mechanism connected therewith to its initial position when the operator releases the treadle.

As the treadle 208 is raised by the spring 218, the pawl 176 which lies in one of the notches 168 and 172 on the near side of the ratchet disk 166 causes said disk, and therefore the gear wheel 162, to be actuated through another quarter turn in the same direction as before, the positions of the parts of the ratchet device being illustrated in Fig. 5 in a partially raised position. The actuation of the gear wheel 162 causes the cooperating gear wheel 160 and the associated quill 152 and cams 18, 20 and 28 to be rotated through a half turn, whereby the various mechanisms of the machine are

actuated and caused to complete the cycle of operation.

From the foregoing description, it is evident that as the treadle mechanism is depressed by the operator and subsequently raised by the power stored in the spring during the depressing movement, the ratchet device is actuated progressively in steps in a single direction whereby the operating cams of the machine are rotated to cause the various mechanisms thereof to function through a complete cycle of operation, after which the parts of the machine come to rest and remain so until the operator again supplies power to the machine through the treadle mechanism.

Although the preferred embodiment of the invention has been set forth as embodying specific structural details and arrangements and locations of parts, those skilled in the art will readily understand that modifications may be made therein without departing from the spirit and scope of the invention.

Having shown and described the preferred embodiment of the invention, that which is claimed as new, is:—

1. A heel-press having, in combination, a movable carrier, a series of heel-clamps mounted thereon, and a foot-power mechanism for advancing said carrier step-by-step comprising a treadle adapted to be actuated downwardly by the operator and means cooperating therewith for raising the treadle and causing both the up and down movements thereof to be effective to advance said carrier.

2. A heel-press having, in combination, a movable carrier, a series of heel-clamps mounted thereon, means for advancing said carrier step-by-step, means for operating said heel-clamps, and foot-treadle mechanism biased to its inoperative position and arranged and adapted to be actuated by the operator through one of its working strokes for supplying power to both of said means during both strokes of said mechanism.

3. A heel-press having, in combination, a movable carrier, a series of heel-clamps mounted thereon, and a foot-power mechanism for advancing said carrier step-by-step comprising a treadle biased to its inoperative position and adapted to be moved downwardly by the operator and a double acting ratchet device operated thereby, said ratchet device being arranged to be actuated to advance said carrier a step during both the up and down movements of said treadle.

4. A heel-press having, in combination, a movable carrier, a series of heel-clamps mounted thereon, and a foot-power mechanism for advancing said carrier step-by-step comprising a ratchet device cooperating with said carrier, means including a treadle for causing said ratchet device to advance said

carrier at each depression thereof, and a power spring in which power is stored during the depression of the treadle for subsequently raising said treadle and causing said 5 ratchet device to advance said carrier.

5. A heel-press having, in combination, a movable carrier, a series of heel-clamps mounted thereon, and a foot-power mechanism for advancing said carrier step-by-step 10 comprising a double-acting ratchet-device cooperating with said carrier, and means including a treadle operatively related to said ratchet-device, said treadle being normally held in its upper inoperative position and 15 adapted to be moved downwardly by the operator for causing said device to advance said carrier during both the up and down movements of said treadle.

6. A heel-press having, in combination, a 20 movable carrier, a series of heel-clamps mounted thereon, and a foot-power mechanism for advancing said carrier step-by-step comprising a member operatively connected to said carrier and provided with a series of 25 shoulders, a plurality of pawls, and means including a treadle mechanism for causing one of said pawls to engage one of certain of said shoulders during each downward movement of said treadle mechanism and the other 30 pawl to engage one of the other shoulders during each upward movement thereof, whereby said carrier is advanced a step during each movement of said treadle mechanism.

35. 7. A heel-press having, in combination, a movable carrier, a series of heel-clamps mounted thereon, and a foot-power mechanism for advancing said carrier step-by-step comprising a treadle and a double-acting 40 ratchet device operatively related to said carrier and comprising a notched member, a plurality of pawls and a plurality of operating arms respectively carrying said pawls and connected to said treadle for causing 45 said pawls to engage said notched member successively as said treadle is depressed and raised.

8. A heel-press having, in combination, a 50 movable carrier, a series of heel-clamps mounted thereon, and a foot-power mechanism for advancing said carrier step-by-step comprising a treadle mechanism for actuating said carrier as the treadle is depressed and means operatively associated with said 55 treadle mechanism for raising said treadle mechanism and actuating said carrier.

9. A heel-press having, in combination, a 60 heel-clamp for engaging the tread face and heel seat face of a heel, an ejector, means for actuating the ejector in the plane of the lifts to release any heel that adheres to the 65 clamp, and spring-actuated means operatively connected to said ejector and rendered operative at a predetermined point in the ac-

tuation thereof for discharging a heel from 65 the clamp.

10. A heel-press having, in combination, a heel-clamp for engaging the tread face and heel seat face of a heel, an ejector for discharging a heel laterally from said clamp, means for advancing and retracting said 70 ejector, and auxiliary means, set during the retracting movement and released during the advancing movement of said ejector, for quickly ejecting a heel therefrom. 75

11. A heel-press having, in combination, a series of movable heel-clamps, means for actuating said heel-clamps through an ejecting station, and means disposed at said ejecting station and operating upon the heels in 80 the successive clamps for gradually releasing any heel that adheres to the clamp and then quickly discharging it therefrom.

12. A heel press having, in combination, a horizontally rotatable carrier, a plurality of 85 heel-clamps supported at the periphery thereof, means for advancing said carrier and heel-clamps step-by-step, and a horizontally disposed ejector operating successively upon the heels in the respective heel-clamps 90 for gradually releasing any heel that adheres to the clamp and then quickly discharging it therefrom.

13. A heel press having, in combination, a horizontally rotatable carrier, a plurality of 95 heel-clamps supported at the periphery thereof, means for advancing said carrier and heel-clamps step-by-step, a radially and horizontally disposed ejector operating successively upon the heels in the respective 100 clamps for engaging and releasing any heel that adheres to the clamps, and auxiliary actuating means cooperating therewith for quickly discharging the heels after they have been engaged and released by said ejector. 105

14. A heel-press having, in combination, a heel-clamp comprising cooperating clamp members, means for effecting relative movements of said members, and foot-treadle mechanism biased to its inoperative position and constructed and arranged to be actuated by the operator through one of its working strokes for supplying power to said means during both strokes of said mechanism. 110

15. A heel-press having, in combination, a heel-clamp comprising relatively movable clamp members, means for closing said members into clamping relation with a heel, means for opening said members to release the heel, and foot-power mechanism for causing the actuation of said clamp opening and closing means in predetermined time relation, said mechanism comprising a treadle adapted to be actuated downwardly by the operator and means cooperating therewith for raising the treadle and causing both the up and down movements thereof to be effective to actuate said clamp opening and clos- 115 120 125

ing means through complete cycles of operation.

16. A heel-press having, in combination, a heel-clamp comprising cooperating clamp members, means for effecting relative movements of said members, and a foot-power mechanism comprising a ratchet-device cooperating with said moving means, means including a treadle for causing said ratchet-device to supply power to said moving means during each depression thereof, and means cooperating with said treadle and in which power is stored during the depression thereof for subsequently raising said treadle and causing said ratchet-device to supply power to said moving means.

17. A heel-press having, in combination, movable means for pressing heels, and foot-power mechanism for actuating said movable pressing means comprising a treadle adapted to be actuated downwardly by the operator, and means cooperating therewith for raising the treadle and causing both the up and down movements thereof to be effective to actuate said movable pressing means.

18. A shoe machine comprising a plurality of correlated mechanisms adapted to oper-

ate in predetermined time relation through successive complete cycles of operation, and foot-power mechanism for actuating said correlated mechanisms comprising a treadle adapted to be actuated downwardly by the operator, and means cooperating therewith for raising the treadle and causing both the up and down movements thereof to be effective to actuate the correlated mechanisms through complete cycles of operation.

19. A heel-press having, in combination, a heel-clamp having a pair of jaws for pressing a heel, means for opening the clamp, and an ejector having a heel engaging and releasing movement and then a continuing heel discharging movement of a different character sufficient in direction and extent to remove the heel from the clamp.

20. A heel-press having, in combination, a movable carrier, a series of heel-clamps supported thereby, and an ejector operating successively on the heels in said clamps having an initial slow movement for releasing any heel that adheres to its clamp and a final accelerated movement for discharging the heel from the clamp.
